UNITED STATES PATENT OFFICE.

WESTON M. FULTON, OF KNOXVILLE, TENNESSEE, ASSIGNOR, BY MESNE ASSIGNMENTS, TO THE FULTON SYLPHON COMPANY, OF KNOXVILLE, TENNESSEE, A CORPORATION OF DELAWARE.

EXPANSIBLE AND COLLAPSIBLE RECEPTACLE.

Application filed August 30, 1922. Serial No. 585,295.

This invention relates to receptacles whose volume may be manually changed without permanently deforming the walls thereof in order to discharge the contained substance, 5 and particularly to the class of receptacles for liquids employed by operatives for applying lubricating liquids to machinery.

It has been proposed heretofore to provide receptacles from which the contained 10 substance may be forced at the will of the operative, wherein the receptacle is provided with a thin sheet metal bottom which, when pressed, will be forced inwardly, thereby slightly decreasing the volume of the receptacle and forcing the contained liquid or 15 other substance out through a suitably-positioned aperture or discharge spout. Devices of this character are open to objection owing to the small amount of the substance, such as 20 lubricating oil, that can be forced out by one movement of the diaphragm bottom, while the repeated distortion of the thin metal bottom eventually results in a fracture adjacent the periphery thereof. It has also 25 been proposed to provide receptacles of this type with a pump arrangement, but the latter is subject to leakage and expensive to manufacture. As disclosed in my U. S. Patent No. 762,300, it has further been pro-

30 posed to mount a corrugated collapsible and expansible vessel within a receptacle to the end that the volume of the latter may be varied by expanding and collapsing said vessel to force the contained substance out 35 when desired. This construction avoids the objections incident to the before-mentioned devices but requires that the corrugated vessel be secured to a member projecting laterally from the side walls of the receptacle.

40 It is an object of this invention to provide a receptacle of the character referred to which avoids the objections incident to devices of the first two types mentioned and which possesses the advantages obtained by 45 the use of a collapsible and expansible wall, and which is more durable, economical to manufacture and simple in construction.

Experience has demonstrated that a corrugated expansible and collapsible wall, although 50 formed of relatively thin metal, is relatively rigid against deformation from rough usage, while a non-corrugated portion

of a lateral wall of a receptacle of the character referred to must be of greater thickness or so reinforced as to be sufficiently rigid 55 to withstand rough usage and prevent undue deformation. Accordingly when the corrugated wall forms a part of the lateral wall of such a receptacle it may be made of thinner metal than the uncorrugated portion of 60 said wall and still be capable of maintaining its form against the rough usage to which devices of this character are commonly subjected.

Another object of the present invention is 65 to provide a receptacle with a body of any desired conformation and having its lateral wall reduced in thickness adjacent the base, such reduced portion being corrugated to provide flexibility and preferably being 70 formed integrally with the upper rigid portion of the body.

Another object of this invention is to provide a receptacle of the character referred to when desired with means supplemental to the 75 elasticity inherent in the wall for returning the collapsible portion to its uncollapsed position from any collapsed position, and, if desired, to provide means for limiting the extent of compression of said collapsible 80 portion.

A further object of this invention is to provide a receptacle of the character referred to with valve means whereby escape of the contained fluid or other substance is prevented 85 when the device is accidentally or intentionally turned to other than its upright position.

A further object of this invention is to provide a device of the type just characterized with means whereby the valve is automatically opened by collapse of the corrugated portion and also, preferably, automatically closed when said corrugated portion expands.

Another object of this invention is to provide a receptacle of the character referred to with means for reinforcing the corrugations of the corrugated portion whereby the same will be capable of withstanding exceptionally hard usage.

Other objects will appear as the description of the invention proceeds.

Stated broadly, the invention comprises a

receptacle including in its lateral wall a relatively rigid portion and a thinner corrugated metal portion preferably integral with said rigid portion and adapted to be manually

5 ly collapsed to vary the volume of said receptacle, thereby forcing the contained liquid or other substance out through a discharge opening in said receptacle.

The inventive idea is capable of receiving 10 a variety of mechanical expressions, some of which, for purposes of illustration, have been shown on the accompanying drawings, but it is to be expressly understood that these embodiments have been selected for the purpose 15 of illustration only, and are not to be construed as definitions of the limits of the invention, reference being had to the appended claims for that purpose.

Referring to the drawings, wherein the 20 same reference characters designate corresponding parts in the several figures:

Fig. 1 is a vertical section, taken on the line 1—1 of Fig. 2, of a receptacle embodying one form of the present invention, and 25 Fig. 2 is an elevation of the receptacle illustrated in Fig. 1.

Fig. 3 is a vertical section of another embodiment of the inventive idea.

Fig. 4 is a detail view, partly in section, 30 of the corrugated portion and strengthening rings of the receptacle illustrated in Fig. 3.

Fig. 5 is a detail view illustrating the valve stem guide employed in the embodiment illustrated in Fig. 3.

35 Figs. 6 and 7 are vertical sections of other embodiments of the present invention.

In the form shown in Fig. 1, 1 is a receptacle for fluid, or "oiler" such as is usually employed in lubricating machinery. The 40 upper portion of its lateral wall consists of a relatively rigid metal portion 2 while the lower portion consists of a thinner, corrugated, flexible portion 3 formed integrally with upper portion 2. The lower end of the 45 receptacle may be closed in any suitable manner as, for example, by means of a separate plate or by means of an integral portion of the metal forming the lateral wall.

In the preferred construction, a rigid plate 50 4 is secured to the lower end of the corrugated portion by having a small portion 5 of the corrugated wall 3 spun over the periphery of the plate and the joint suitably sealed, as by solder. If desired, plate 4 may 55 have formed therein a circular bead 6 to increase its strength and to serve as a support on which the receptacle will rest when set in a vertical position.

Any suitable means may be employed to 60 provide a discharge opening or spout. In the embodiment illustrated in Fig. 1, a flanged member 7 is suitably secured, as by solder, in an opening in rigid portion 2 of the receptacle. Threaded into member 7 is an exten- 65 sionally threaded nut 8 provided with a

knurled flange 9 and having rigidly attached thereto in any suitable way a tapered discharge spout 10 of any suitable size and shape.

Resilient means may be provided to insure 70 that the corrugated portion 3 will be returned to its uncollapsed position or to supplement the inherent elasticity of said corrugated portion from any collapsed position. This means may comprise a spring 11 75 positioned at its upper end around the lower flange 12 of threaded member 7, and at its lower end centered by a circular bead 13 formed in rigid plate 4. Spring 11 preferably has its coils so spaced that when corrugated portion 3 has been compressed near its elastic limit, the coils thereof will contact and serve as a safety stop to prevent further collapsing of the corrugated portion. Spring 11 also serves to expand corrugated portion 80 3 from its collapsed position, and if desired, spring 11 may be of such length and strength as to normally hold corrugated portion 3 expanded beyond its unstressed position, so that, in compressing corrugated portion 3 to 90 eject the contained liquid or other substance, the collapsible portion of the wall will have its range of collapse and expansion divided to a greater or less extent on each side of its unstressed position, that is the position it 95 would take if no force were applied to either expand or contract it. It is to be expressly understood however that spring 11 is not an essential part of the invention, but may be omitted and reliance placed on the inherent 100 resilience of the corrugated portion of the wall to return said portion to expanded position.

In place of relying upon the coils of the spring 11 contacting to prevent excessive 105 collapse of the corrugated portion 3, said receptacle may be provided interiorly (as shown in dotted lines in Figure 1) with a cylindrical wall 14, which is preferably perforated, and which will engage the movable 110 end wall of the receptacle and prevent excessive collapse of the same. Said cylindrical wall 14 may be mounted in position in any suitable way, as by securing its end to the flange on the member 7. If desired, 115 however, the stop for limiting the extent of collapse of the corrugated portion 3 may be entirely omitted.

The operation of the oiler is as follows:—

The knurled nut 8 carrying spout 10 having been removed, oil or any other suitable substance is placed in the receptacle through the opening thus provided, after which nut 8 is threaded back into position. When it is desired to eject the contained substance, the receptacle is held so that pressure can be exerted against end plate 4 and, upon forcing the latter toward the spout, the volume of the receptacle is decreased, thereby 125 ejecting whatever quantity of the substance 130

is required. Upon removal of pressure from plate 4, the resilience of corrugated portion 3, together with the spring 11, if employed, causes the same to return to its normal position. If too great pressure is exerted upon plate 4, the coils of spring 11 contact and thus prevent the further collapse of the corrugated portion, or where stop 14 is employed it serves the same purpose. Bottom 10 wall or plate 4 is preferably formed of relatively thick metal, but it is to be expressly understood that it may be made of thin flexible metal if desired without departing from the spirit of this invention.

15 In Fig. 3 there is illustrated another embodiment of the invention which is particularly adapted for hard usage, such as an automobile oiler to be carried in an automobile tool box. Experience has shown that 20 automobile oilers are usually thrown into the tool box and not only have tools thrown in on them at random, but, when the car is traveling over rough roads, these tools are jostled about and thrown against the oiler, 25 denting and damaging the same. The jolting of the car is moreover such that the oiler is usually thrown into a position where oil escapes from the spout. The construction illustrated in Fig. 3 comprises a rigid wall 30 portion 2, a thinner corrugated wall portion 3, an end plate 4, and a spout-carrying member 8 similar to that previously described. Interiorly of the discharge spout and adjacent to the lower end thereof is suitably secured a valve seat 15 adapted to receive a ball valve 16 which carries a rod 17 that extends in both directions from the ball valve. The upper portion 18 of rod 17 passes through the central aperture of a perforated 40 guide member 19 secured in any suitable manner to the interior of the discharge spout 10, at a convenient distance above valve seat 15, while the lower end of rod 17 extends approximately into contact with the 45 end plate 4 when the valve is on its seat and said end wall is in expanded position. Guide member 19 may be economically manufactured on a stamp-press by being punched from sheet-metal with suitable dies. A 50 spring 20, surrounding the upper portion 18 of rod 17, abuts at its upper end against the underside of guide member 19 and at its lower end against ball valve 16 in such a manner that said spring tends to maintain 55 valve 16 on its seat 15, thereby normally preventing the escape of fluid or other substance contained in the receptacle. Openings 21 are provided in guide member 19 to permit the substance contained in the receptacle 60 to be readily ejected.

If desired, the corrugated, flexible wall portion 3 may be reenforced in any suitable manner in order to increase the strength thereof or decrease the wear encountered by 65 the receptacle when carried in a tool box.

Preferably, wire rings 22 are expanded into the outer bends of the corrugations. Fig. 4 illustrates the method of inserting these rings in the corrugations, which consists in collapsing them, as illustrated in the dotted 70 line position 22', so that they may be inserted inside of the corrugated wall, and then allowing them to expand into the corrugations which they are intended to reinforce, so that, in their expanded position the ends 75 thereof will abut as at 23 and prevent the collapse of the same due to pressure applied around the periphery thereof.

Instead of using rings 22 for reenforcing the corrugated wall portion, or in conjunction therewith, metal bands 24 may be employed in the manner described in my U. S. Patent 1,151,777, dated Aug. 31, 1915, but it is preferable that these bands be made thick and quite rigid, instead of resilient as disclosed in the above-mentioned patent.

The operation of this embodiment of the invention is as follows:

The knurled member 8, together with spout 10, are removed from flanged member 7 as previously described, the valve means being necessarily removed by the same operation. Any desired liquid or other suitable substance is inserted into the receptacle and knurled member 8 is threaded back into position. In order to eject the contained substance, pressure is applied to end plate 4, as by the operative's thumb, whereupon the corrugated portion 3 is collapsed and end plate 4, in contact with the lower end of rod 17, carries the rod upward and unseats ball valve 16 to allow the substance to pass out through valve seat 15 and openings 21 in guide member 19, rod 17 being guided in its upward movement by guide member 19. 100 When pressure is removed from plate 4, the resilience of corrugated portion 3, together with the pressure exerted by spring 20 acting through rod 17, forces plate 4 to assume its normal position, thereby reestablishing the normal volume of the receptacle, and allowing valve 16 to engage valve seat 15. Regardless of the position the receptacle may assume, valve 16, held on its seat by means 105 of spring 20, prevents escape of the substance contained in the receptacle.

While the rigid portion of the lateral wall of the receptacle is preferably made of thicker metal than the corrugated flexible portion, this is not essential, as the uncorrugated portion may be rendered rigid in any other suitable way. Thus, as illustrated in Fig. 6, the upper portion 2 of the lateral wall may be made of the same thickness as the corrugated portion 3, and said uncorrugated 120 portion 2 may be reenforced by a cup-shaped or bell-shaped member 25 suitably held in position as a backing for the wall portion 2, as by spinning the upper portion 26 of said wall portion 2 around the edge of the open- 125

ing in said member 25 which receives the flanged member 7. This construction possesses the advantage that the relatively thin wall 2, 3 may be composed of brass or copper, while the thick reinforcing member 25 may be made of steel, which is much less expensive, whereby the cost of materials employed may be reduced. Furthermore, steel being stronger than brass or copper, the same amount of strength is secured with a less thickness and weight of material. Otherwise the construction shown in Fig. 6 is substantially the same or may be the same as shown in the previous figures.

15. In place of connecting the discharge spout with the body of the receptacle in the manner shown in Figs. 1 to 6, any other suitable means for securing a discharge spout in communication with the body of the receptacle may be employed. One suitable construction is illustrated in Fig. 7, wherein the upper portion of the body of the receptacle is reduced to a neck 27 in which are suitably formed threads 28 for engagement 25 with the threads of a ferrule 29 having a perforated bottom 30 and an outwardly directed flange 31. A discharge spout 10 of any suitable form and size is suitably secured, as by solder, in the aperture of the 30 perforated bottom portion 30 of said ferrule, and cooperating with the flange 31 of the said ferrule is a cap piece 32 also suitably secured, as by solder, to the spout 10 and having its outer periphery spun or bent 35 around said flange, as shown at 33, to retain a gasket 34 of leather or other suitable material for engagement with the upper portion of the neck 27, to make a fluid-tight joint therewith when the ferrule 29 is screwed 40 into said neck 27. The advantage possessed by a structure such as just described is that all of the parts may be readily formed of sheet metal and the screw threads rolled into the same.

45. While I much prefer to make the flexible corrugated portion 3 of the lateral wall of the receptacle integral with the rigid portion 2 of said wall, it is within the contemplation of this invention to make the 50 flexible corrugated portion separate from the rigid uncorrugated portion of the lateral wall and suitably attach the two portions together, as by soldering or brazing. This has been illustrated in Fig. 7, wherein the 55 upper portion 2 is made separate from the corrugated flexible portion 3 and the two sections suitably joined at 35. The end wall 4 in this arrangement may be provided as a separate plate as illustrated, but when 60 the corrugated portion 3 is made separate from the rigid portion 2 the end wall 4 may be readily formed integral with the corrugated lateral wall. The rigid portion 2 of the lateral wall is preferably made of thicker 65 material than the corrugated portion 3 as in

the embodiments heretofore described so that, while a construction wherein the corrugated portion is made separate from the uncorrugated portion of the lateral wall does not possess all of the advantages of the preferred 70 construction wherein these portions are made integral, a device of this character still possesses the advantage that the uncorrugated portion of the lateral wall may form a continuation of and be made thicker than 75 the corrugated portion, and thereby possess the capacity of withstanding rough usage while saving in the weight and thickness of material in the corrugated flexible portion.

It will therefore be perceived that a receptacle constructed in conformity with the present invention possesses the advantage of durability, simplicity of construction, and economy of manufacture, particularly where the lateral wall is composed of relatively 80 rigid and corrugated flexible portions which are integral. In the latter event the lateral wall can be manufactured from a single piece of material and thereby avoid the labor and material involved in making a 85 soldered or mechanical joint where the two 90 portions are connected. The integral construction also eliminates the danger of leakage at the joint. Moreover, by making the uncorrugated portion of the lateral wall 95 thicker than the flexible corrugated portion thereof, the former possesses a rigidity and capacity to withstand rough usage equal to that which is inherent in the corrugated portion, while the use of thinner material in 100 the corrugated portion not only saves weight and thickness of material, but also increases the flexibility of the same and thereby renders the device more easy of operation.

Where the uncorrugated portion of the lateral wall is made integral with and of greater thickness than the corrugated portion, the uncorrugated portion is preferably merged gradually into the corrugated portion by gradually reducing the thickness of 110 the wall as illustrated at 36 in Figs. 1 and 3. While not essential, this gradual decrease in the thickness eliminates the line of weakness that might otherwise exist were there an abrupt change of thickness in the 115 wall.

While the embodiments illustrated on the drawings have been described with considerable particularity, it is to be expressly understood that the invention is not restricted thereto as the same is capable of receiving a variety of mechanical expressions some of which will now readily suggest themselves to those skilled in the art. While features of construction have been 120 illustrated only in conjunction with certain embodiments of the invention, it is to be expressly understood that they may be employed if desired with other embodiments of 125 the invention; thus the reinforcement of the 130

bends of the corrugations illustrated in Fig. 3 may be employed in any of the other embodiments illustrated; the use of an inner reinforcing member as shown in Fig. 6 may 5 be employed in any of the other embodiments illustrated; the valve mechanism illustrated in Fig. 3 may be employed in other embodiments of the invention, etc. Moreover, changes may be made in the details of 10 arrangement, construction and proportion of the various parts, and certain features used without other features, without departing from the spirit of this invention. Reference is therefore to be had to the 15 claims hereto appended for a definition of the limits of this invention.

What is claimed is:

1. A receptacle comprising a body portion having its lateral wall reduced in thickness and corrugated adjacent the base thereof, said corrugated portion having a closed end constituting the base of said receptacle upon which it normally rests and a discharge-spout secured to said body portion 25 above said corrugated portion.

2. A receptacle comprising a body provided with an integral lateral wall which is of reduced thickness and corrugated adjacent the base thereof, and a discharge-spout 30 secured to said body.

3. A receptacle having a lateral wall comprising a rigid wall portion and a thinner corrugated wall portion integral with said rigid wall portion.

35 4. A receptacle having integrally formed lateral wall portions comprising a rigid portion and a thin corrugated portion, said rigid portion being provided with a discharge opening.

40 5. A receptacle having integrally-formed, lateral wall portions comprising a rigid portion and a thinner corrugated portion, said rigid portion being provided with a discharge opening, and a plate secured to the end corrugation of said thin corrugated portion to form a closure for said receptacle.

50 6. A receptacle having lateral wall portions comprising a rigid portion and a corrugated, collapsible portion integral therewith, a discharge spout secured to said rigid portion, and means for limiting the extent of compression of said collapsible portion.

55 7. A receptacle having lateral wall portions comprising a rigid portion and a thinner corrugated, collapsible portion, a discharge spout secured to said rigid portion, and means cooperating with said corrugated, collapsible portion for returning the same to uncollapsed position from any collapsed position.

60 8. A receptacle having lateral wall portions comprising a rigid portion and a thinner corrugated collapsible portion, having a closed end, a discharge spout secured to said

rigid portion, a valve means in said spout, 65 and means operable by the closed end of said collapsible portion for operating said valve means.

9. A receptacle having integrally-formed lateral wall portions comprising a rigid portion and a corrugated collapsible portion, and means for limiting the compression of said collapsible portion and returning the corrugated portion to uncollapsed position from any collapsed position. 75

10. In a device of the class described, the combination of a body having lateral walls comprising a rigid portion and a thin corrugated portion, a discharge spout secured to said rigid portion, a valve seat secured in 80 said spout, a valve for closing said seat, said valve having a stem extending in opposite directions from said valve, a perforated member secured to said spout, and resilient means positioned between said member and said valve for normally maintaining said valve in seated position. 85

11. In a device of the class described, the combination of a body having a lateral wall comprising a rigid portion and a thin corrugated portion, a ring in the outer bend of each corrugation of said corrugated portion, and discharge means secured to said rigid portion. 90

12. In a device of the class described, the combination of a body having a lateral wall comprising a rigid portion and a thinner corrugated portion, said corrugated portion having a closed end constituting the base of said receptacle upon which it normally rests, 100 a reinforcing band secured to the outer bend of each corrugation of said corrugated portion, and discharge means secured to said rigid portion. 105

13. In a device of the class described, a body comprising in its lateral wall a relatively rigid portion and adjacent the base thereof a corrugated flexible portion integral with said rigid portion and adapted to be collapsed, a discharge spout through which the contained fluid may be discharged by collapse of said corrugated portion, and means in said spout to prevent loss of the fluid when said corrugated portion is not collapsed. 110

14. In a device of the class described, a body comprising in its lateral wall, a relatively rigid portion and adjacent the base thereof a corrugated flexible portion integral with said rigid portion and adapted to be collapsed, a discharge spout through which the contained fluid may be discharged by collapse of said corrugated portion, a valve in said spout, and means operable by the collapse of said corrugated portion for opening said valve. 120

15. In a device of the class described, a body comprising in its lateral wall a relative-

ly rigid portion and adjacent the base thereof a corrugated flexible portion integral with said rigid portion and adapted to be collapsed, a discharge spout through which the contained fluid may be discharged by collapse of said corrugated portion, a valve in

opened when said corrugated portion is collapsed and means for closing said valve and simultaneously expanding said corrugated portion. 10

In testimony whereof I have signed this specification.

WESTON M. FULTON.
